UNITED STATES PATENT OFFICE

GORDON F. CANE, OF SAN FRANCISCO, CALIFORNIA, ASSIGNOR, BY MESNE ASSIGNMENTS, TO THORN THOMPSON, OF SAN FRANCISCO, CALIFORNIA

MOUNTING MEANS FOR FOLDABLE ROLL-ABOUT BEDS

Application filed July 23, 1929, Serial No. 380,818. Renewed July 22, 1932.

This invention relates to foldable beds of the roll-about type and more particularly to a novel means of connection between the bed frame and a wheeled, freely movable supporting carriage therefor.

An object of the invention is to generally simplify and improve the construction and operation of beds of the character described by providing a comparatively simple, strong and compact means for effectively maintaining the equilibrium of the bed with a relatively small, light weight carriage of minimum depth.

Another object of the invention is to provide a bed of the character described in which the bed frame will be disposed in a desirably low plane when in position of use.

A further object is to provide a bed of the character described in which the tilting tendency of the carriage during movement of the bed into and out of operative position is effectively minimized.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claim.

Referring to the drawings,

Figure 1 is a fragmentary side elevation of the bed of my invention as when in folded or up-ended position.

Figure 2 is a fragmentary side elevation of the bed as when extended for use.

Figure 3 is a fragmentary side elevation of the bed as when in a position intermediate of the folded and extended positions.

Figure 4 is a fragmentary horizontal sectional view taken on the plane of line 4-4 of Figure 1.

Figure 5 is a vertical sectional view taken on the plane of line 5-5 of Figure 1.

The present embodiment of the bed of my invention as shown in the accompanying drawings comprises a bed frame 6 which is

arranged for rotation about a horizontal axis on a wheeled carriage or truck 7.

Means of operative connection between the bed frame and truck is especially constructed and arranged in accordance with this invention to provide the improvements and advantages as herein described. In this embodiment said means primarily comprises front and rear links 8 and 9 pivotally connected at their ends with the side rails 10 of the bed frame and with the truck 7 respectively. The bed pivot points 11 and 12 of the links are located in spaced relation to one another at points spaced well inwardly from the head end 14 of the bed frame and are arranged to be disposed over portions of the truck approximately midway of the front and rear ends of the latter when the bed is in upended position. Furthermore the pivots 11 and 12 are arranged to be disposed over the truck when the bed is extended and the rear pivots 12 substantially overlie the rear end or better, the rear floor engaging points of the truck whereby the truck is held down effectively during up-ending as well as extension movement of the bed.

Referring now to the truck pivots, it will be noted that the front links 8 are pivoted as at 15 on the truck directly over the front floor engaging points of the latter, whereas the rear link truck pivots 16 are located below the plane of the pivots 15 and approximately midway between the rear floor engaging points of the truck and a point midway between the front and rear ends of the truck.

It will now be apparent that during movement of the bed from vertical to extended position, the axis of rotation of the bed is caused to move rearwardly of the center of gravity of the truck whereby the truck is utilized in the most advantageous manner for insuring the equilibrium of the structure.

It will also be noted that in view of the fact that the bed frame pivotal points of the links are located well inwardly spaced from the head end 14 of the bed frame and the latter projects beyond the rear end of the truck when in operative position, the center of gravity of the bed will be in relatively 100

close proximity to the axis of rotation of the bed and to the center of gravity of the truck, whereby not only will the tilting tendency of the truck be materially lessened but the balancing of the bed frame may be effected through the medium of simple counter-balancing means of minimum size.

Attention is directed to the fact that the bed frame pivots 11 and 12 of the links 8 and 9 are spaced horizontally a materially greater distance from truck pivot 15 of the front link than from the truck pivot 16 of the rear link, and that the rear bed pivot 12 lies rearward of all other pivots, when the bed is in extended or horizontal position. In such position the front link bed pivots 11 lie approximately over the truck pivots 16 of the rear links. By this arrangement the head end 14 of the bed is disposed rearward of the rear end of the truck, the truck will effectively maintain the bed in equilibrium during rotation of the bed on its axis, and the bed frame is disposed in a desirably close-to-the-floor position when extended.

Another factor making for stability is that the front links 8 are comparatively long and thereby dispose the truck well forward of the head end 14 of the bed. This increases the rear overhanging of the bed relative to the truck and thus throws the weight to the rear, whereby the truck better supports the structure and the tilting tendency thereof is materially lessened as compared to an arrangement where little or no rearward extension or overhang of the bed rearward is provided.

As particularly shown in Figure 4, counterbalancing means is provided in the form of springs 20 mounted on the truck 7 and connected with the rear links 9 through the medium of links 21. As this means is not here claimed as a part of the present invention, it is sufficient to say that said means operates to counterbalance the bed structure during movement into and out of operative position. Likewise shown in the drawings is a means 22 for locking the bed and truck against relative movement in the event of tilting of the truck and as this means is not claimed as part of the present invention further description is unnecessary. Other parts shown, but not here claimed, are the means 19 for extending and folding of the front leg 23 of the bed, and the head piece 24 and its associated parts. It is to be noted, however, that the counterbalance means and the locking means may be made of small, light construction due to the particularly efficient means of this invention for connecting the bed frame and truck in such manner as to insure maintaining the equilibrium of the bed and truck during rotation of the bed on its axis.

Referring now more specifically to the means of connection of this invention, it will be noted that the rear links 9 are L-shaped

so that they may be positioned as are the links 8, inwardly of the sides of the bed frame and as shown in Figure 1 permit the head end 14 of the bed to nest within the rear links.

It is desirable to provide a stop means to prevent downward movement or sagging of the bed after movement into position of use. As here shown, the arcuate arms 25 of the locking means 22 and the mountings 26 for the counterbalance springs 20 offer a convenient arrangement for providing the said stop means. Consequently as the arms 25 are fixed to the front links 8 and move past said mountings 26 on the truck, said arms are offset between their ends to define shoulders 27 which when the bed is extended, as shown in Figure 2, will lie upon the mountings 26 and thereby prevent further downward movement of the bed frame relative to the truck.

It will now be understood that the disposition of the bed pivots 12 rearwardly of all other pivots, the use of relatively long front links, and the other hereinbefore described locations of the several pivots as well as the location of truck pivots 15 and 16 adjacent the front and rear extremities of the truck, provide for effectively maintaining the equilibrium of the structure with a simple means of connection and a small, compact, and light weight truck of minimum depth.

I claim:

In a roll-about foldable bed, a wheeled truck, an upending bed frame, front and rear links pivotally connected to said truck and bed frame, the connecting points of the front and rear links with the truck being respectively disposed adjacent to the front and rear extremities of the truck whereas the frame connecting points of the front links are disposed over a point substantially midway of the front and rear extremities of the truck and the frame connecting points of the rear links are located over and substantially in line with the rear extremity of said truck when the bed frame is extended for use, said rear links being substantially L shaped and having portions thereof extended under the frame when the latter is in upended position.

In testimony whereof I have hereunto set my hand at Oakland, California, this 18th day of July, 1929.

GORDON F. CANE.
